CLAIM

We claim the ornamental design for a hole saw arbor substantially, as shown and described.

DESCRIPTION

FIG. 1 is a front, top, and left side perspective view of a hole saw arbor showing our new design;
FIG. 2 is a left-side elevational view thereof;
FIG. 3 is a right-side elevational view thereof;
FIG. 4 is a front elevational view thereof;
FIG. 5 is a rear elevational view thereof;
FIG. 6 is a top plan view thereof;
FIG. 7 is a bottom plan view thereof;
FIG. 8 is a rear, top, and left side perspective view thereof;
FIG. 9 is a front, bottom, and left side perspective view thereof; and,
FIG. 10 is a rear, bottom and left side perspective view thereof.

The broken lines in the drawings illustrate portions of the hole saw arbor that form no part of the claimed design.
